(57) **CLAIM**

The ornamental design for a ball head of a portable stand for an electronic device, as shown and described.

DESCRIPTION

FIG. 1 is a perspective view of a ball head of a portable stand for an electronic device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the ball head of FIGS. 1-7 included in an exemplary portable stand for an electronic device.

The broken lines shown in FIGS. 2-7 represent bounds of the claimed design and form no part thereof. The broken lines shown in FIG. 8 depict an exemplary environment in which the claimed ball head design may be used, and form no part of the claimed design.

1 Claim, 8 Drawing Sheets
